(57) **CLAIM**

I claim the ornamental design for a combined child safety barrier and locking element, as shown and described.

DESCRIPTION

FIG. 1 is a perspective view illustrating a front of a child safety barrier and locking element embodying a first aspect of my new design, illustrated in an extended position;

FIG. 2 is another perspective view of the front of the child safety barrier and locking element of FIG. 1;

FIG. 3 is a rear elevational view of the child safety barrier and locking element of FIG. 1;

FIG. 4 is a right profile view of the child safety barrier and locking element of FIG. 1;

FIG. 5 is a left profile view of the child safety barrier and locking element of FIG. 1; and,

FIG. 6 is a top plan view of the child safety barrier and locking element of FIG. 1.
